STACY B. HASELTINE, OF CHICAGO, ILLINOIS, ASSIGNOR TO W. H. MINER, INC., OF CHICAGO, ILLINOIS, A CORPORATION OF DELAWARE

PIVOTAL YOKE AND COUPLER CONNECTION

Application filed February 25, 1929. Serial No. 342,350.

This invention relates to improvements in pivotal yoke and coupler connections for railway draft riggings.

One object of the invention is to provide a pivotal coupler and yoke connection for railway draft riggings including a coupler key and a cooperating pivot pin for connecting the coupler and yoke to transmit draft forces, wherein the coupler shank 10 pivots on the pin in draft and the pin also serves as a retaining means for preventing accidental removal of the key.

A further object of the invention is to provide a pivotal connection between the coupler 15 and the yoke of a railway draft rigging, including a coupler key and a pivot pin, the key extending through an opening in the coupler shank and aligned key receiving openings provided in the yoke, and the pin 20 extending through the coupler shank in a direction transverse to the key and having bearing engagement in a seat provided at the rear edge portion of the key so as to allow lateral pivotal swinging movement of the 25 coupler with respect to the key and yoke, the coupler key opening of the shank having the front wall provided with a curved bearing seat in which a curved bearing enlargement of the key is accommodated, wherein the 30 pivot pin maintains the interengaging bearing relation of the enlargement and the bearing seat and also prevents accidental removal of the key, means being also provided for holding the pivot pin against removal.

35 Other and further objects of the invention will more clearly appear from the description and claims hereinafter following.

In the drawings forming a part of this specification, Figure 1 is a horizontal, longitudinal sectional view of a portion of the under-frame structure of a railway car at one 40 end of said car, and Figure 2 is a longitudinal vertical sectional view, partly broken away, corresponding substantially to the line 2—2 45 of Figure 1.

In said drawings, 10—10 indicate the usual spaced center or draft sills of the railway car underframe, the same being provided with cheek plates 11—11 on the inner sides 50 thereof, having transverse inner end shoul-

ders 12 serving as front stop lugs. The cheek plates 11 and the sills are provided with aligned transverse coupler key receiving openings 13—13 of usual form. The striking casting of the car is designated by 14 and is provided with an opening adapted to accommodate the inner end of the ordinary coupler shank. The bottom of the opening is closed by the usual carry iron member 15 which is secured to the bottom of the striking casting and has a wear plate 16 mounted thereon. The shock absorbing mechanism of the railway draft rigging, only the outer end portion of which is shown, is designated generally by the character 17. The shock absorbing mechanism used for illustrative purposes only in this instance is shown as of the friction shell type comprising the usual friction shell, friction shoes 18—18, and wedge block 19 cooperating therewith, it being understood that the friction shell contains the usual spring resistance which opposes inward movement of the shoes and wedge. The friction shock absorbing mechanism has a main follower 20 cooperating therewith, the follower 20 being interposed between the wedge 19 and the stop lugs 12.

In carrying out my invention, I provide, broadly, a coupler A, a yoke B, a coupler key C, and a pivot pin D.

The coupler A has the usual coupler head 21 at the outer end thereof, only part of the same being indicated. The coupler shank is supported by the carry iron and rests on the wear plate 16. The inner end of the coupler shank abuts the main follower 20 and the follower 20 is forced inwardly in the usual manner by the coupler during a buffing action. The yoke member B, the forward end only of which is illustrated in the drawings, is of the well known hooded type having spaced top and bottom arms 22—22, the forward ends of which form the top and bottom walls of the hood and spaced side walls 23—23 connecting the top and bottom walls and defining the side walls of the hood. The side walls 23 are provided with aligned transverse coupler key receiving openings 24—24. As will be understood, the rear end portions of the arms 22 are connected by the usual

vertical end member of the yoke, not shown. The shock absorbing mechanism is compressed between the end member of the yoke and the front follower 20 in the usual manner during a draft action or outward movement of the coupler and yoke and is compressed between the follower 20 and the usual rear stop lugs, not shown, of the draft sills upon inward movement of the coupler in buff.

10 The coupler shank is provided with a transverse coupler key receiving opening 25 of special design. As shown, the coupler key receiving opening 25 has the front end wall thereof provided with a concave bearing seat 15 or surface 26 extending transversely of the coupler shank. The rear end wall of the opening 25 is preferably straight transversely but curved vertically in the usual manner.

As more clearly shown in Figure 2, the 20 bearing surface of the front end wall 26 of the coupler key receiving opening is also curved or of convex formation in a vertical direction. The coupler shank is also provided with a vertical pin receiving opening 25 25 27 which intersects the rear portion of the key receiving opening of the coupler shank. The bottom wall of the hood of the yoke is also provided with a vertical opening 28 of larger diameter than the pin receiving opening 29 27 of the coupler shank.

The coupler key C, which is employed to connect the coupler shank and yoke and guide the parts for longitudinal movement, extends through the key receiving opening 25 of the 35 shank, the openings 24—24 of the yoke and the key receiving openings 13—13 of the draft sills. As most clearly shown in Figure 1, the forward edge portion of the coupler key C is provided with a curved enlargement 40 29 forming a bearing member cooperating with the seat 26. The enlargement 29 has a transverse convex surface formation which is also vertically curved so as to properly cooperate with the seat 26. At the rear edge, 45 midway between the opposite ends of the key, the same is provided with a curved seat or opening 30 adapted to cooperate with the pivot pin D. The pivot pin D serves as a pivotal connection between the coupler shank 50 and the key C during both the draft and buffing action of the mechanism, and serves as means for transmitting the pulling forces from the coupler shank to the coupler key and yoke during outward movement of the 55 coupler in draft.

The pin D is of substantially cylindrical form and is mounted in the vertical pin receiving opening 27 of the coupler shank and extends through the bearing opening or seat 60 30 at the rear edge of the key C, the curved outer surface of the pin fitting the seat 30 so as to provide true pivotal swinging movement between the pin and the coupler key. As will be evident, the coupler is thus mounted 65 ed for pivotal swinging movement with re-

spect to the key and the yoke, the pin at the same time holding the bearing projection 29 of the key in cooperating relation with the bearing seat 26 on the front end wall of the key receiving opening of the coupler shank, thereby preventing endwise removal of the coupler key. By providing the pivot pin connection just described, no additional retaining means is necessary for preventing removal of the coupler key.

In assembling the parts after insertion of the coupler key C through the openings of the coupler shank, the yoke and the draft sills, the pin receiving opening 27 is brought into alignment with the opening 28 in the bottom wall of the hood and the pin inserted through the opening 28 into the opening 27 of the shank. After the pin has been applied, the same is held against dropping through the opening 28 by a supporting plate 31 which overlies the opening and engages the bottom end of the pin D. As most clearly illustrated in Figure 2, the plate has a down-turned flange 32 at the outer end thereof, adapted to abut the front edge of the bottom wall of the hood and is secured in position by a cotter pin 33 extending through the bottom wall of the hood and the plate 31.

During a buffing action, the coupler A will be forced inwardly, carrying the follower 20 therewith and compressing the shock absorbing mechanism directly. During this action, when the key has been moved inwardly with respect to the yoke, the same will be free to swing with the coupler, but in the event of either one or both ends of the key engaging the front end walls of the slots of the yoke, swinging movement of the coupler with respect to the yoke and key C is accommodated by the pivot pin D. In this connection, it is pointed out that the inner surfaces of the side walls of the hood are flared outwardly in the usual manner to permit the necessary lateral movement of the coupler shank when cars are being operated on curved track.

When a draft action is applied to the coupler A, the pin D is pulled outwardly therewith, and, inasmuch as the pin directly engages the key C, the latter is carried forwardly therewith and, by engagement with the front end walls of the key openings 24 of the side members of the yoke, pulls the yoke outwardly and effects compression of the shock absorbing mechanism in the usual manner. As will be evident, pivotal swinging movement of the coupler with respect to the key is permitted by the pivotal connection between the pin D and the rear edge of the key, the bearing projection at the front end of the key and the cooperating bearing seat 26 of the coupler shank allowing the pivotal movement about the center of the pin without danger of disengagement of the coupler shank and key.

An important advantage is obtained by providing the pivotal connection rearwardly of the coupler key by means of the pivot pin, in that the amount of rocking movement of the coupler butt on the follower 20 is reduced to a minimum.

While I have herein shown and described what I consider the preferred manner of carrying out my invention, the same is merely illustrative and I contemplate all changes and modifications which come within the scope of the claims appended hereto.

I claim:

1. In a railway draft rigging, the combination with a coupler having a shank member provided with a transverse key receiving opening, the front wall of the opening being provided with a bearing seat; of a yoke member having aligned coupler key receiving openings; a coupler key extending through the openings of the shank and yoke, said key having a bearing enlargement rigid therewith at the forward edge adapted to engage within the bearing seat, said coupler key having a curved bearing seat at the rear edge thereof; a pivot member mounted in the coupler shank extending transversely of the key and having a curved bearing portion engaging within the seat of the key holding said bearing enlargement of the key seated in the seat of the key receiving opening and preventing endwise removal of the key.

2. In a railway draft rigging, the combination with a coupler having a shank member provided with a transverse key receiving opening, said opening having a transversely extending concave seat on the front wall thereof, and a pivot pin receiving opening intersecting the inner end of the key receiving opening; of a yoke having aligned coupler key receiving openings; a coupler key having an integral convex bearing projection at the forward side thereof, engaged within the concave bearing seat and a pivot pin receiving opening at the rear side, said key extending through the opening of the coupler shank and the aligned openings of the yoke; a pivot pin mounted in the pivot pin opening of the coupler shank and extending through the pivot opening of the coupler key and holding the bearing projection of the key in said seat, thereby preventing endwise removal of the key; and means for maintaining the pivot pin assembled with the coupler shank.

3. A pivotal yoke and coupler connection for railway draft riggings including: A yoke member having a hood defined by spaced top and bottom and spaced side walls, said side walls having aligned coupler key receiving openings; a coupler having a shank provided with a horizontal transverse key receiving opening having a curved bearing seat on the interior front wall of the opening; a key connecting the coupler shank and yoke, extending through said key receiving openings of

the shank and yoke, said key having a curved bearing projection cooperating with the curved bearing seat and a concave bearing face on the rear side thereof; and a pin connecting the coupler shank and key for pivotal movement, said pin extending vertically through the coupler shank and pivotally engaging said concave bearing surface of the key, the bottom wall of the yoke being provided with an opening through which the pin is insertable and removable; and means for closing said last named opening to prevent removal of the pin from the coupler shank.

In witness that I claim the foregoing I have hereunto subscribed my name this 21st day of February, 1929.

STACY B. HASELTINE.
